DESIGN FOR A DRESS

Mildred Wagner, New York, N. Y.

Application July 26, 1937, Serial No. 70,634

Term of patent 3½ years

To all whom it may concern:

Be it known that I, Mildred Wagner, a citizen of the United States of America, residing in city of New York, county of New York, and State of New York, have invented a new, original, and ornamental Design for a Dress, of which the following is a specification, reference being had to the accompanying drawing, forming part thereof.

Figure 1 is a front view of a dress showing my new design.

Figure 2 is a rear view thereof.

My design is characterized by the stitched tabs on the neck portion of the contrasting embroidered jacket member; which tabs have a contrasting edging in association with similar edging around the neckline of the jacket member and on the belt as shown.

I claim:

The ornamental design for a dress substantially as shown and described.

MILDRED WAGNER.
